UNITED STATES PATENT OFFICE.

ARTHUR MIDDLETON ROSE, OF YONKERS, NEW YORK, ASSIGNOR TO MATTHEW J. WHITTALL, OF WORCESTER, MASSACHUSETTS.

DESIGN FOR CARPET.

SPECIFICATION forming part of Design No. 24,493, dated July 16, 1895.

Application filed June 8, 1895. Serial No. 652,178. Term of patent 3½ years.

To all whom it may concern:

Be it known that I, ARTHUR MIDDLETON ROSE, residing at Yonkers, county of Westester, State of New York, have invented and produced a new and original Design for a Pattern to be Wrought into Wilton and other Carpetings in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of a body A and a border B.

The body A is decorated with wreaths or garlands of roses and their foliage, together with large open scrolls.

The border B shows a narrow water-marked band on the inner edge and has at intervals 20 a large vase surrounded by roses and garlands similar to those in the body, and above it are two spreading scrolls.

What I claim as my invention, and desire to secure by Letters Patent, is— 25

1. In a design for a carpet, the body A, substantially as shown.
2. In a design for a carpet, the border B, substantially as shown.
3. The design for carpets, consisting of the 30 body A, and the border B, substantially as shown.

ARTHUR MIDDLETON ROSE.
